EXPLOSIVE INITIATOR

William R. Brockway, Thorofare, and George A. Noddin, Mantua, N.J., assignors to E. I. du Pont de Nemours and Company, Wilmington, Del., a corporation of Delaware

Filed June 11, 1962, Ser. No. 291,420

5 Claims. (Cl. 102—28)

The present invention relates to explosive initiators and more particularly to explosive initiators so encased and of such physical characteristics that the effective forces of their explosive action are largely directed in a predetermined direction.

The art has long recognized the dangers inherent in conventionally used explosive initiators. Commercially available initiators contain from 6 to 13 grains of a high-energy detonating composition, loadings great enough to cause severe damage to the operator and surrounding equipment should accidental actuation of the initiator occur. However, since the success of any explosive operation depends to a large extent upon the reliable initiation of the explosive charge, there has been a general reluctance to decrease the explosive loading of the initiator charges. Prior attempts to devise safer initiators have involved highly complicated assembly techniques and complex ignition devices.

In accordance with this invention, we now provide an initiator of improved safety and reliability characteristics which is capable of initiating even relatively insensitive explosives and which utilizes conventional bridge plug assemblies, safety fuse, and low energy connecting cord. Our novel initiator comprises a tubular shell having two extremities, one of the extremities being integrally closed by a closure member of lesser thickness than the sidewalls of the shell, and an ignition assembly inserted into and closing the other extremity, the shell having positioned sequentially therein from said integral closure member, a base charge, a priming charge, and an ignition charge, said base and priming charges each being at a loading of up to about 1 grain, and the combined columnar length of said base and priming charges within said shell being at least about $\frac{1}{4}$ inch.

In a preferred embodiment of this invention, the loading of the detonating charge is 0.5–0.7 grain and the loading of the priming charge is 0.3 to 0.7 grain, and the ratio of the depth of the combined layers of priming and detonating charges to the diameter of these layers is about 1.5 to 3.0.

To facilitate the use of conventional bridgeplug assemblies, safety fuse, and low energy connecting cord as the ignition assembly in the initiator of this invention, that portion of the shell surrounding the ignition assembly in a particularly preferred embodiment of our invention has a diameter greater than that of the portion surrounding the base charge and the priming charge.

Conveniently, in one preferred embodiment of this invention, the initiator is adapted to provide a delayed firing action by positioning a delay element of the conventional type between the ignition and the priming charge.

In order to describe the initiator of this invention in greater detail, reference is made to the accompanying drawings wherein:

FIGURE 1 is a vertical, cross-sectional view of an initiator in accordance with this invention wherein the ignition assembly is electrically actuated.

FIGURE 2 is a vertical, cross-sectional view of a non-electrically actuated initiator in accordance with this invention, and

FIGURE 3 is a vertical, cross-sectional view of an electrically actuated delay initiator in accordance with this invention.

2

FIGURE 4 is a modified form of the electrically actuated delay initiator of FIGURE 3.

The electric initiator of FIGURE 1 includes a shell 1 having a closed extremity 2 of lesser thickness than the side walls of the shell. The portion 3 of the shell adjacent the closed end is of lesser diameter than the remaining portion of the shell 1. Within the portion of this shell of reduced diameter is a base charge 4 and pressed into a conical cavity in this charge is a priming charge 5. The ignition assembly in this particular unit consists of a high resistance bridgewire 6 imbedded in a loose mass of ignition composition 7 and attached to and held in position by lead wires 8 which are in turn held in place by, and pass through, a sealing plug 9 of a resilient material. Peripheral crimps 13 hold the plug in place.

In FIGURE 2, the elements are as in FIGURE 1, with the exception that the ignition assembly in this particular unit is a low-energy connecting cord as described in U.S. Patent 2,982,210 having an explosive core 10, a metal sheath 11, and counteracting 12. One end of this cord is inserted into the open extremity of the shell, so that the inserted end is adjacent the priming charge 5, and the shell 1 is crimpingly engaged about the portion of the cord in the shell.

In FIGURE 3, the elements are again as in FIGURE 1 with the exception that a delay element, consisting of a charge of a deflagrating composition 14 encased in a heavy-walled metal tube 15, is interposed between the ignition assembly and the priming charge 5.

The elements of FIGURE 4 are as in FIGURE 3; however, the lesser diameter portion of the shell contains the delay assembly.

The operation of the initiator of the invention is identical to that of conventional initiators, i.e., the priming charge is actuated by the burning ignition charge (which is ignited by a hot bridgewire or spark from safety fuse or an arc gap) or the delay charge when present, or by the detonation of the connecting cord, and initiates the base charge. The initiating impulse generated by the detonation of the base charge is concentrated axially downward due to the decreased resistance offered by the thin bottom of the shell and the depth of the charge with relationship to its diameter, so that the initiating effect at 2 of the assembly is at least as effective as that of initiators containing from 6 to 13 grains of detonating explosive as the base charge. The depth of the base charge in relationship to its diameter is critical—if the amount of base charge in a conventional initiator is reduced, a very thin layer of the explosive composition results, and energy from its detonation is spread over a larger area. Consequently the initiating impulse is inadequate even if the bottom of the shell is thinner than the sidewalls. In our initiator wherein the ratio of the combined depth of the base and priming charges to the diameter of the charge is preferably from about 1.5 to about 3.0, the energy from the detonation is concentrated in a small area so that the initiating impulse is focused for maximum effect without dissipation of the initiation impulse. In the present assembly, the side walls may vary in thickness from about 0.005 to about 0.030 inch, but the bottom thickness should not exceed 0.017 inch.

The following examples illustrate specific embodiments of this invention. These examples are to be understood to be illustrative only and not limiting the invention in any way.

Example I

A series of initiators was assembled as shown in FIGURE 2. The shells were of aluminum, with a 0.017 inch wall thickness, and a closed extremity thickness as set forth in Table I. The inner diameter of a 0.313 inch long portion adjacent the closed extremity was 0.125 inch. The inner diameter of the remaining portion of the shell

was 0.260 inch. The total height of each of the shells was 0.9875 inch. Into these shells were loaded base charges of pentaerythritol tetranitrate (PETN) pressed at 50 lbs., dead weight, and priming charges of lead azide. In each case, the depth of the combined charge was 0.313 inch, the depth of the reduced diameter portion of the shell. A six-inch length of low-energy connecting cord having an explosive loading of 0.78 grain of lead azide was crimped into each shell. The detonating power of these initiators was tested by embedding each of the initiators into a cut stick of dynamite comprising 9.0% nitroglycerine, 69% ammonium nitrate, 3.0% sodium nitrate, 10% salt, 2% sulfur, 1.7% pulp, 4.8% meal and 0.5% chalk. The results of testing the initiators is given in Table I.

Test Number	Bottom Thickness, inch	Loading at 50 lbs. with Flat Pin (grains)		Result
		Lead Azide	PETN	
1	0.016	1.0	0	D ¹
2	0.016	0.6	0.5	D
3	0.016	0.2	0.5	D
4	0.005	0.5	0.5	D
5	0.005	0.2	0.5	D
6	0.003	1.0	0	D
7	0.003	0.5	0.5	D
8	0.003	0.4	0.5	D
9	0.003	0.3	0.7	D

¹ D = Dynamite detonated.

Example 2

A series of electric initiators was prepared similar to those shown in FIGURE 1. The sidewalls of the shell were of 0.017 inch thick aluminum whereas the aluminum closing one end of the shell was 0.003 inch thick. The outer diameter of the upper portion of the shell was 0.260 inch. The outer diameter of the lower, closed extremity of the shell, 0.25 inch high, was 0.125 inch and its inner diameter was 0.108 inch. Into this smaller diameter portion of the shell 0.6 grain of pentaerythritol tetranitrate was loaded as a base charge, and, above this charge was placed 0.5 grain of lead azide, each charge being pressed into position in the reduced diameter portion of the shell by 50 lb. pressure. The ignition assembly inserted into the larger diameter portion of this initiator consisted of a 0.0019 inch diameter nickel-chromium bridge wire soldered to the lead wires inserted in a rubber plug to provide a $\frac{1}{8}$ inch span and projecting $\frac{1}{8}$ inch from the base of the rubber plug. The bridgewire was embedded in a 0.6 grain loose charge of a 50/25/25 mixture of ground smokeless powder/bis-basic lead-4,6-dinitro-O-cresylate/potassium chlorate which was contiguous to the upper surface of the priming charge.

To test for static resistance, the lead wires of the thus assembled initiator were twisted together and connected to the high voltage line of a "leg-to-shell" static sensitivity testing equipment consisting essentially of a source of variable voltage and a series of picofarad condensers ranging in capacitance from 250 to 2000 picofarad, and the shell was connected to a ground line. Voltages from 0 to 30,000 volts were applied to a condenser of known capacitance in increments of 2000 volts, and the condenser was allowed to discharge through the initiator. The initiator detonated when a voltage of 26,000 volts applied through a condenser of 250 picofarad was discharged through it, indicating that the initiator has a static resistance greater than 24,000 man equivalent volts (m.e.v.). [One man-equivalent volt is defined as the energy of a condenser of 0.0003 μ farad capacitance charged to a potential of 1 volt (an average man has a capacitance of 0.003 μ farad).]

When the initiator was connected to a conventional blasting circuit, ignition occurred when a 5 ampere (6.85 volt) current was passed through the bridgewire.

The lack of violence of the initiators was apparent.

Visual inspection of the fired initiators showed that the sides were only slightly bulged whereas the base of the initiator was fragmented. When the initiators were placed base downward on an aluminum plate (1 inch x 1 inch x $\frac{1}{2}$ inch) and initiated, a dent 0.032 inch in diameter was formed in the plate, indicating the effectiveness of initiation action. However, when the initiators were placed within a hollow tin cylinder two inches in diameter and five inches high, which served to detect missiles, and actuated, the tin cylinder showed no perforations.

The shell may be constructed of a metal, e.g., thin gauge copper, commercial bronze, other copper alloys, aluminum, or of a polymeric material having comparable structural strength and rigidity. As may be seen, the thickness of the shell at its closed extremity should be sufficient to retain the charges yet less than that of the side walls of the shell so that upon detonation of the explosive charges, the explosive action will be to a large extent concentrated in the axial direction. The exact length of the shell will depend upon the size of the charges, and the nature of the ignition assembly, and the length of the delay element, if any, to be incorporated in the initiator.

The particular compositions used for the various charges are not critical to the present invention. Accordingly, for the base charge, any of the conventional base charges may be used, e.g., pentaerythritol tetranitrate (PETN), lead azide, cyclotrimethylenetrinitramine (RDX), nitromannite, TNT or cyclotetramethylenetrinitramine (HMX). As the priming charge, heat-sensitive detonating compositions such as lead azide, diazodinitrophenol, or mercury fulminate may be used. Obviously when squib action is desired, the ignition composition, the primary charge, and the base charge may be identical.

Advantageously, a variety of commercially available ignition assemblies can be sealed into the shell, for example by means of a resilient plug of the conventional design used in initiators. Suitable ignition means include electrical assemblies such as a bridgewire and bead arrangement, a bridgewire inserted into a loose mass of ignition composition, an "exploding" bridgewire, and an arc-firing system in which the bridgewire is omitted.

Alternatively, the ignition assembly may be of the non-electric type wherein a detonation-transmitting cord, such as, for example, low-energy connecting cord as described in U.S. Patent 2,982,210, or safety fuse is used to initiate the priming charge. In this case the cord may be inserted directly into the shell and the shell sealed about it, as, for example, by crimping.

Delayed firing action of the initiators, for example for sequential blasting operations, is provided by the delay element of the predetermined interval interposed between the ignition assembly and the priming charge. These trains comprise a length of deflagrating composition, e.g., boron and red lead, silicon and red lead, or barium peroxide and selenium among others, in a heavy-walled tube as of lead or aluminum.

Obviously many modifications and variations of the present invention are possible in the light of the above teachings. It is therefore to be understood that within the scope of the appended claims, the invention may be carried out otherwise than specifically described.

What is claimed is:

1. An initiator which comprises a tubular shell having two extremities, one of the extremities being integrally closed by a closure member of lesser thickness than the sidewalls of the shell, and an ignition assembly inserted into and closing the other extremity, the shell having positioned sequentially therein from said integral closure member, up to about 1 grain of base charge, up to about 1 grain of priming charge, and an ignition composition, said base and priming charges having a combined columnar length of at least about $\frac{1}{4}$ inch and being in peripheral contact with the shell, the ratio of said length

to the diameter of said charges being from about 1.5 to about 3.0.

2. An initiator according to claim 1 wherein a delay element is interposed between said priming charge and said ignition assembly.

3. An initiator as in claim 1 wherein the loading of said priming charge is between about 0.3 and 0.7 grain and the loading of said base charge is between about 0.5 and about 0.7 grain.

4. An initiator as in claim 1 wherein the thickness of said closure member is from about 0.003 to about 0.016 inch and the thickness of the said side walls is from about 0.005 to about 0.030 inch.

5. An initiator comprising a tubular shell having side walls about 0.005 to about 0.03 inch thick integrally closed at one end by a closure member about 0.003 to about 0.016 inch thick, said closure member being thinner than said side walls, and an ignition assembly inserted into and closing the other end of the shell, said shell containing

in sequence from said closure member, between about 0.5 and about 0.7 grain of base charge, between about 0.3 and 0.7 grain of priming charge, and an ignition composition, the base and priming charges having a combined columnar length of at least about $\frac{1}{4}$ inch and being in peripheral contact with the shell, the ratio of said length to the diameter of said charges being from about 1.5 to 3.0, the portion of the shell housing the base and priming charges being of lesser diameter than the portion 10 of said shell housing the ignition assembly.
